(57) **CLAIM**

The ornamental design for a dental flosser with light, as shown and described.

DESCRIPTION

FIG. 1 is a first side view of a dental flosser with light; FIG. 2 is a second side view of the design of FIG. 1; FIG. 3 is a third side view of the design of FIG. 1; FIG. 4 is a fourth side view of the design of FIG. 1; FIG. 5 is a top view of the design of FIG. 1; FIG. 6 is a bottom view of the design of FIG. 1; FIG. 7 is a perspective view of the design of FIG. 1; and, FIG. 8 is a perspective view of the design of FIG. 1 showing parts in an alternative position.

The broken lines shown in the drawings represent portions of the dental flosser with light that form no part of the claimed design.
